Specification for Design.

Patented Dec. 20, 1921.

Application filed February 28, 1921. Serial No. 448,613. Term of patent 14 years.

To all whom it may concern:

Be it known that I, GEORGE J. MEYERS, of Council Bluffs, Pottawattamie county, Iowa, a citizen of the United States, have invented a new, original, and ornamental Design for a Tobacco-Pipe Reamer, reference being had to the accompanying drawings, forming a part thereof, in which—

Figure 1 is a perspective view of the device.

Fig. 2 is a side elevation of the same; and Fig. 3 shows a section along the line 3—3 of Fig. 2 and looking in the direction of the arrows.

I claim:

The ornamental design for a smoking pipe reamer as shown.

GEORGE J. MEYERS.
